UNITED STATES PATENT OFFICE.

HAROLD MASON DE GRAW, OF NEW LONDON, CONNECTICUT, ASSIGNOR TO ELECTRIC BOAT COMPANY, A CORPORATION OF NEW JERSEY.

DIVING-RUDDER GEAR FOR SUBMARINE BOATS.

1,250,987.

Specification of Letters Patent. Patented Dec. 25, 1917.

Application filed September 16, 1916. Serial No. 120,442.

To all whom it may concern:

Be it known that I, HAROLD M. DE GRAW, a citizen of the United States, and a resident of New London, in the county of New London and State of Connecticut, have invented certain new and useful Improvements in Diving-Rudder Gears for Submarine Boats; and I do hereby declare the following to be a full, clear, and exact description of the invention, such as will enable others skilled in the art to which it appertains to make and use the same.

This invention provides a novel and exceedingly simple operating gear for the diving-rudders of submarine boats.

According to the invention, each diving-rudder is provided with a rudder shaft which is inclined to the plane of the rudder in such manner that turning the rudder shaft through about 180° will swing the rudder from the extended to the retracted position, while slight angular movements of the shaft about the extended position will tilt the rudder for diving or rising. As a result, universal joints or the like are dispensed with; and yet each rudder may easily be retracted, extended, or tilted for steering.

The invention will be most clearly understood from the following description, taken in connection with the accompanying drawings, of which Figure 1 is a top plan view of a portion of the bow of a submarine boat equipped with the improved diving gear; Fig. 2 is a section on the line 2-2 of Fig. 1; Fig. 3 is a perspective looking to the right of Fig. 1; and Fig. 4 is a side elevation of a bow rudder when extended, certain other locations of the rudder being shown in broken lines.

The general arrangement of the diving-rudders with respect to the hull of the boat is shown in Fig. 1, from which it will be seen that when the rudders 3 are extended they project horizontally on opposite sides of the boat, and when shipped or retracted into inoperative position they lie flat against the inclined sides of the superstructure 4 which overlies the hull 5 and are nested in pockets 6. In this case the diving-rudders are shown at the bow; but they may be applied at the stern or elsewhere, as is well known.

Referring to Figs. 2 and 3, an operating shaft 7, mounted in suitable bearings 8, has keyed thereon a worm 9, meshing with two worm-gears 10. Each worm-gear is keyed on an inclined pintle or shaft 11 mounted in suitable bearings 12 and 13. The outboard end of each inclined shaft 11, which projects beyond the superstructure, has secured thereto one of the rudders 3. The shaft bearings 8 and 12 are carried by a base 14, anchored to a foundation 15 suitably fixed in place on top of hull 5. The shaft bearings 13 are supported by the superstructure 4. The shaft 7 is preferably inclined as illustrated, in order that at its rear end it may carry an operating hand-wheel or the like (not shown) located inside the hull 5.

The parts as adjusted in Figs. 1 and 3 show the rudders extended with their flats horizontal. The rudders are now in operative condition, but they will act merely as steadyng devices for the fore part of the boat when the latter is so balanced and trimmed that the rudders are submerged. The rudders have been brought to this extended position by means of the rotation of the single operating shaft 7, in the direction of the arrow 16. A slight rotation of the same operating shaft will now tilt the rudders 3 forward or aft, as shown at 30 and 40 in Fig. 4, to impart in the well known manner a downward or upward inclination to the bow during propulsion of the boat.

The fact that the tip of each rudder has a slight forward or aft movement when the rudder is tilted does not interfere at all with successful steering. To return the rudders to shipped position, the only operation necessary is a rotation of the shaft 7 in a direction opposite to that of arrow 16. Thus, in every case, and for all adjustments, only the single operating shaft 7 is employed.

During the upward and inward sweep of a rudder 3 to its shipped position the rudder in succession assumes the locations 50, 60 and 70 as shown in Fig. 4. During the downward and outward sweep of the rudder to its extended position it of course assumes in succession the locations 70, 60 and 50. As will be seen from a comparison of Figs. 1 and 4, some point 3^m on the rudder's edge

3^a will traverse a path 3^p during the movement of the rudder from its retracted to its extended position. Thus, although a rotation of either shaft 11, through an angle of approximately 180°, swings its rudder from its retracted to its extended position or vice versa, according to the direction of rotation of the shaft, the pockets 6 may be made very shallow throughout and yet adequately shield the rudders 3 when they are retracted.

Obviously, when moving the rudders from retracted to extended position, each rudder may be swung so that its tip descends in a semi-circle forward of the shaft 11; in which case it might be desirable to make slight changes in the pockets 6 or to dispense with them altogether. It will also be clear that if desired the rudders could be arranged for movement so that when retracted to lie in against the superstructure they would hang below their shafts 11, and this as the result merely of reversing the inclination of the shafts, that is inclining each shaft downwardly and outwardly.

I claim:

1. In a submarine boat, the combination of a pair of shafts extending outwardly through side walls of the boat, rudders carried rigidly upon the outer ends of the shafts and each disposed at an incline to the axis of its shaft, and means for rotating the shafts to carry the rudders to inoperative positions adjacent to the side walls of the boat and to operative positions extending outwardly from the side walls of the boat and to adjust the angular positions of the rudders while they are in the operative positions.
2. In a submarine boat, the combination of a pair of shafts extending outwardly through side walls of the boat and at an incline to the horizontal, rudders carried rigidly on the outer ends of the shafts and each disposed at an incline to the axis of the shaft, and means for rotating the shafts.

3. A submarine boat having a superstructure provided with upright side walls, a pair of shafts mounted for rotation within the superstructure with their ends projecting through openings in the side walls, rudders rigidly fixed on the outer ends of the shafts, each at an incline to the axis of its shaft, and means for simultaneously rotating the shafts to carry the rudders to substantially vertical positions against the adjacent side walls and to substantially horizontal positions projecting out from the side walls and to adjust the angular position of the rudders for steering the boat in a vertical plane.

4. A submarine boat having a superstructure provided with upright side walls, a pair of shafts mounted for rotation within the superstructure substantially transverse to the length of the boat and at an incline to

the horizontal, each shaft having its end projecting through an opening in one of the side walls, rudders rigidly fixed on the outer ends of the shafts outside the superstructure, each at an incline to the axis of its shaft, and means for simultaneously rotating the shafts to carry the rudders to substantially vertical positions adjacent the upright side walls and to substantially horizontal positions projecting out from the side walls and to adjust the angular position of the rudders for steering the boat in a vertical plane.

5. In a submarine boat, in combination, a pivotally mounted elongated rudder, and a rudder operating mechanism the elements of which are simultaneously actuated to move the rudder from a retracted position wherein the longitudinal axis of the rudder is substantially vertical to an extended position wherein the longitudinal axis of the rudder is substantially horizontal.

6. In a submarine boat, in combination, a pivotally mounted elongated rudder, and a rudder operating mechanism the elements of which are simultaneously actuated to move the rudder from a retracted position wherein the longitudinal axis of the rudder is substantially vertical to an extended position wherein the longitudinal axis of the rudder is substantially horizontal, said mechanism being capable of moving the rudder when extended about its longitudinal axis for steering.

7. In a submarine boat, in combination, a support, an elongated rudder adjustably mounted on the support, and means for swinging the tip of the rudder in a curved path lying in an inclined plane while turning the rudder about its longitudinal axis to move the rudder from a retracted to an extended position.

8. In a submarine boat, in combination, a pair of rudder shafts extending transversely of the boat and inclined downwardly and toward each other, a rudder mounted on each shaft at such an angle to the axis of the shaft that in one position of rotation of the shaft the rudder will be substantially in a horizontal plane, and means for rotating the shafts to move the rudders from retracted to extended positions.

9. In a submarine boat, in combination, a pair of rudder shafts extending transversely of the boat and inclined downwardly and toward each other, a rudder mounted on each shaft at such an angle to the axis of the shaft that in one position of rotation of the shaft the rudder will be substantially in a horizontal plane, and means for rotating the shafts to move the rudders from retracted to extended positions and for turning the shaft when the rudder is extended for steering.

10. In a submarine boat, in combination, a pair of rudder-shafts extending trans-

versely of the boat and inclined downwardly and toward each other, a rudder fixedly offset from each shaft adjacent to its outboard end and arranged at an angle to the axis of its said shaft greater than a right angle, a pair of worm-wheels one fixed on each shaft adjacent to its inboard end, and a worm- shaft engaging both worm-wheels and rotatable to move the rudders from a retracted to an extended position and also for steering.

In testimony whereof I affix my signature.

HAROLD MASON DE GRAW.
